UNITED STATES PATENT OFFICE.

WILLARD J. BELL, OF WEEDSPORT, NEW YORK.

DESIGN FOR A MOP-BUCKET.

SPECIFICATION forming part of Design No. 26,849, dated March 30, 1897.

Application filed January 12, 1897. Serial No. 619,003. Term of patent 14 years.

To all whom it may concern:

Be it known that I, WILLARD J. BELL, a citizen of the United States, residing at Weedsport, in the county of Cayuga, State of New York, have invented and produced a new and original Design for Mop-Buckets, of which the following is a specification, reference being had to the accompanying drawings, in which—

Figure 1 shows a side view of the design complete. Fig. 2 is a top plan view thereof. Fig. 3 is a longitudinal section over the center thereof, these three views being deemed necessary to properly illustrate the same.

The leading feature of my design consists in a mop-bucket, its form and configuration being substantially as shown in the drawings.

A is an elongated body comprising vertical side and end walls *a*, having their edges turned over, forming a bead or rim *b*.

c is a shelf within the body, extending half-way across the same and to which is secured a perforated cone *d*, this perforated cone being the device which wrings the major part of the water out of the mop by twisting it therein.

e is a bail secured upon the sides by means of ears *f*.

Having described my invention, what I claim, and desire to secure by Design Letters Patent, is—

The design for a mop-bucket, substantially as herein described and shown.

In witness whereof I have hereunto set my hand this 11th day of January, 1896.

WILLARD J. BELL.

In presence of—

MARY A. FRANKLIN,
HOWARD P. DENISON.
